UNITED STATES PATENT OFFICE.

WYLE T. WILSON, OF PHILADELPHIA, PENNSYLVANIA.

FOLDED CARDBOARD RECEPTACLE.

1,334,687.

Specification of Letters Patent. Patented Mar. 23, 1920.

Application filed May 19, 1919. Serial No. 298,197.

To all whom it may concern:

Be it known that I, WYLE T. WILSON, a citizen of the United States, residing at Philadelphia, in the county of Philadelphia and State of Pennsylvania, have invented 5 certain new and useful Improvements in Folded Cardboard Receptacles; and I do hereby declare the following to be a full, clear, and exact description of the invention, 10 such as will enable others skilled in the art to which it appertains to make and use the same.

This invention relates to folded cardboard receptacles especially adapted for use 15 as tobacco containers, and has for its object to provide a receptacle of this character which will be simple in construction and less costly to manufacture than the metal containers heretofore proposed.

20 With these and other objects in view the invention consists in the novel details of construction and combinations of parts more fully hereinafter disclosed and particularly pointed out in the claims.

25 Referring to the accompanying drawings, forming a part of this specification in which like numerals designate like parts in all the views:—

Figure 1 is a perspective view of one form 30 of completed box made in accordance with this invention;

Fig. 2 is a horizontal sectional view of the form of the invention shown in Fig. 1;

Fig. 3 is a longitudinal vertical sectional 35 view, taken along the line 3—3 of Fig. 2;

Fig. 4 is a vertical cross sectional view 40 taken on the line 4—4 of Fig. 3;

Fig. 5 is a diagrammatic plan view of the blank from which the box shown in Figs. 40 1—4 is folded;

Figs. 6, 7 and 8 are fragmentary perspective views illustrating successive steps in the folding of the blank shown in Fig. 5, to produce the lid of the box;

45 Fig. 9 is a view similar to Fig. 5 illustrating a blank adapted to produce a somewhat modified form of lid or closure;

Figs. 10, 11 and 12 are fragmentary perspective views showing successive steps in 50 the folding of the blank illustrated in Fig. 9;

Fig. 13 is a perspective view of a box provided with a still further modified form of closure;

Fig. 14 is a horizontal sectional view of 55 the form of the invention shown in Fig. 13;

Fig. 15 is a fragmentary vertical sectional

view taken on the line 15—15 of Fig. 14; and

Fig. 16 is a diagrammatic plan view of the blank from which the form of the invention illustrated in Figs. 13—15 may be folded. 60

Referring more particularly to Figs. 1 to 8 inclusive, 1 indicates the paper or cardboard blank from which the preferred form of the invention is made, and the said blank 65 is provided with the scored or creased lines 2, 3, 4 and 5, providing the inner and outer front walls 6 and 7, the rear wall 8 and the side walls 9 and 10, as shown. The said wall 7 is scored or creased as at 11 to provide an end member 12; the wall 8 is scored as at 13 to provide an end member 14, the wall 10 is scored as at 15 to provide a tab 16; and the wall 9 is scored as at 17 to provide a tab 18, and the members 12, 14, 70 16, and 18 are completely severed from one another by the cuts 19, 20, and 21, as will be clear from Fig. 5.

A hollow plug like hinged closure member 20 is attached to the wall 8 as by the 80 scored line 21, and its parts are scored as at 22, 23, 24, and 25 to provide closure members 26, 27, 28, 29 and 30, and the said member 28 is further provided with the ears 31 and 32, adapted to be folded along the 85 scored lines 33 and 34, and 35 and 36, respectively, as will presently appear. The member 26 is provided with the small extended portions 37, and also with a substantially semicircular tab 38, completely 90 severed therefrom along the line 39 as shown.

In setting up the box the body is first formed by folding the walls 6, 7, 9 and 10 along the lines 2, 3, 4 and 5 as will be 95 readily apparent, after which the end members 12, 14, 16, and 18 are folded along the lines 11, 13, 15 and 17 respectively, and secured in the positions illustrated in Figs. 2, 3 and 4, by glue or other suitable adhesive. 100 The said plug like hinged closure is then formed by folding the ears 31 and 32 along the lines 33 and 34, and 35 and 36 respectively, as shown in Fig. 6, after which the members 29 and 30 are folded along the 105 lines 24 and 25 respectively as shown in Fig. 7, and secured by a suitable adhesive. The hollow plug closure is next folded along the lines 23 and 22, and glued or otherwise secured, when it will appear in a hollow 110 plug form as in Fig. 8 after which the tab 38 may be folded down to lie substantially

flush with the member 26. It will be observed that the extensions 37 of the said member 26 will take against the walls 9 and 10, acting as stops to prevent the entire 5 plug closure from being pushed too far inwardly.

In the somewhat modified form of the invention shown in Figs. 9 to 12, the body portion of the box, and the permanent closure remain the same, but the method of folding the hinged closure is somewhat different. The closure 40 consists of the members 41, 42, 43, 44, and 45 secured by the scored lines 46, 47, 48 and 49, and the member 42 is provided with the extensions 50 and 51, adapted to be folded along the scored lines 52 and 53, and 54 and 55, respectively, as will presently appear. The member 44 is provided with the projections 20 56 similar to the projections 37 above disclosed, in connection with Figs. 1-8, and the said member 44 is also provided with the tab 57 similar to tab 38 above mentioned.

The manner of folding this form of the 25 invention will be clear from Figs. 10, 11 and 12, of the drawings, but may be briefly set forth as follows:

The entire closure 40 is first folded along the line 21, and the extensions 50 and 51 are 30 bent back along the lines 52 and 53, and 54 and 55 respectively, as shown in Fig. 10. The members 42, 43 and 44 are next successively folded along the lines 46, 47, 48 and 49 to the positions shown in Fig. 11, after 35 which the closure is completed as shown in Fig. 12, by inserting the member 45 between the members 41, 50 and 51, and suitably securing the parts in place by adhesive material.

40 In the form of the invention shown in Figs. 13 to 16, the lid or closure 60, instead of being attached to the wall 8 as in the two preceding forms is shown attached to the wall 6, although it will be obvious that if 45 desired, the said closure 60 may in this case be attached to the wall 8. The said closure as shown in Fig. 16 is scored as at 61, 62, 63 and 64 providing the members 65, 66 and 67, and the tab or finger piece 68 and the member 66 is provided with the ears 69 and 70 each provided with an extension 71, adapted to form a stop member similar to the members 37 and 56, and adapted to be folded along the lines 72 and 73, and 74 and 55 75 respectively.

The closure in the present instance is formed by bending the various members 65, 66, 67, 68, 69, 70 and 71 along the scored lines 61, 62, 63, 64, 72, 73, 74 and 75, and 60 securing the same with adhesive material as will be clear from Figs. 13, 14 and 15.

During the past few years the cost of tin, which has been heretofore the principal material from which tobacco containers have 65 been made, has so advanced as to make its

use almost prohibitive. However, the present invention provides a relatively inexpensive substitute for the said metal containers, and actual use has proven these 70 cardboard containers to possess sufficient strength and rigidity to withstand all ordinary usage as long as their contents last. Further, the cardboard lends itself readily to the printing and lithographing processes 75 which are usually employed for decorating the cans, and identifying and advertising the tobacco contained therein.

It will be observed that in all the forms there is provided a comparatively strong 80 hinged closure which enters within the body portion of the box, reinforcing the same and helping to maintain the shape thereof. Further, this said closure lies substantially 85 flush with the said body portion, and is prevented from being pushed too far inwardly, 90 after the contents are partly used, by the stop members such as 37, 56 and 71, thereby preventing the leakage and waste of tobacco. If desired, the hollow closures 95 shown in Figs. 1 to 12, after being suitably waterproofed and perforated as by holes in the members 28 and 42, may be provided with a sponge or other absorbent material adapted to hold moisture for keeping the tobacco in good condition.

It is obvious that those skilled in the art may vary the details of construction, as well as the arrangement of parts without departing from the spirit of the invention, and therefore I do not wish to be limited to the 100 above disclosure, except as may be required by the claims.

What I claim is:—

1. In a folded blank box the combination of a body portion comprising front, back 105 and side walls; flap members integrally associated with said walls, adapted to be folded and secured to constitute a permanent closure for one end of said body portion; and a hollow plug like closure member 110 integrally connected to one of said walls, comprising a plurality of flaps adapted to be folded over upon one another and secured to form a single hollow plug like reinforcing hinged closure for the other end of said 115 body portion, one of said last mentioned flaps being provided with an integral operating tab and a plurality of ears adapted to 120 coact with the side walls of said body to limit the entrance of said hinged closure within said body portion, substantially as described.

2. In a folded blank box the combination of a body portion comprising front, back and side walls; a plurality of flap members 125 associated with said walls adapted to be folded and glued to form a permanent closure for one end of said body portion; an inner reinforcing front wall adapted to be secured to said first named front wall; 130

and a plurality of members associated with one of said walls adapted to be folded and glued to form a rigid hollow plug like hinged reinforcing closure adapted to enter within 5 said body portion and to lie substantially flush therewith, one of said last mentioned members being provided with an operating tab and with a plurality of extensions constituting stops whereby said hinged closure is

maintained in said flush position, substantially as described.

In testimony whereof I affix my signature in presence of two witnesses.

WYLE T. WILSON.
